COLLAPSIBLE SUPPORT FOR CURTAINS

Robert R. De Ment, Cleveland, Ohio

Application April 29, 1935, Serial No. 18,822

4 Claims. (Cl. 135—7.1)

This invention relates to an improved construction of collapsible support for curtains.

This curtain support is especially adapted for use in providing suitable background for a funeral ceremony, although the general structure may be used in other connections.

As will be readily understood, there are many instances in which the surroundings are not well suited as a background for a funeral ceremony.

10 For instance, wall space afforded in a comparatively small home may be entirely too cramped and the interior decorations of the home might not be at all becoming as a suitable setting or background for such a ceremony. This is especially true in connection with the background and setting for the casket itself and it is therefore desirable for the undertaker to be equipped with a temporary background which can be readily set up in the home so as to overcome the 20 untoward conditions therein prevailing by providing a more suitable setting.

It is therefore the object of the present invention to devise a readily collapsible and extensible support for a curtain which may be conveniently carried by the undertaker to the home and there temporarily set up and later removed with the same degree of convenience.

25 A further object consists in devising such a collapsible support in which the several parts may be assembled and disassembled in a most convenient and efficient manner and in which the curtain may be suspended therefrom without any hinderance thereto.

30 A further object consists in providing such a collapsible support in which there may be effected an adjustment of the supporting bar for the curtain so as to provide a different outline of the background afforded by the curtain.

Another object consists in devising such a 35 structure in which the parts may be manufactured in an expeditious manner so as to avoid unnecessary expense and labor.

Other objects will appear from the following 40 description and claims when considered together with the accompanying drawings.

Fig. 1 is a front elevation of my device with the curtain suspended therefrom and illustrates the general assembly thereof;

Fig. 2 is an enlarged detail of one of the collapsible uprights and part of the top transverse bar supported thereby;

Fig. 3 is a view of one of the upright supports in collapsed condition;

Figs. 4 and 5 are views taken on lines 4—4 and 55 5—5 of Fig. 2.

Fig. 6 is a view of one of the end sections of the top transverse bar; and

Fig. 7 is a view of one of the middle sections of the top transverse bar.

It is to be understood that the present disclosure is merely for purposes of illustration and that many other modifications and variations may be made without departing from the spirit of the present invention as herein set forth and claimed.

10 The two upright supports are altogether independent of each other so that they may be readily collapsed and extended and placed in any position desired. These two upright supports rest directly upon the floor. Both of these supports are of duplicate construction and a description of one of them will therefore suffice for both.

15 Each of the two upright supports rests upon the collapsible legs 1 after the manner of the well-known tripod. Accordingly, the legs 1 are pivoted at their upper ends to their collar member 2 which surrounds and is adapted to slide along the lower tubular section 3 while the legs 1 are pivotally connected near their middle points 20 to the intermediate bars 4 which are pivoted at their other ends to the bracket 5 on the lower end of the tubular section 3. This construction of the collapsible legs will readily be understood, reference being had to Fig. 2 in which the legs are 25 in distended or supporting position while in Fig. 3 the legs are in collapsed condition.

30 The upper end of the hollow tubular section 3 has slidably mounted therein the intermediate hollow tubular section 6 which in turn has extensibly mounted therein the upper hollow tubular section 7. These several hollow tubular sections are adapted to be collapsed as indicated in Fig. 3 for purposes of shipment and are adapted also to be extended for use as indicated in Fig. 2. 35 When in extended position, the sections 6 and 7 are maintained in such position by means of the pins 8 and 9 which are inserted through holes in these sections and are adapted to rest upon the upper ends of the other sections in which they are 40 mounted, as will be clearly understood from Fig. 2. As indicated in the drawings, the sections 6 and 7 may be provided with any number of holes 45 10 so as to permit the extension of the support to any height desired.

50 The upper open end of the hollow tubular section 7, when in extended condition, is adapted to receive the leg 11 which depends from the under side of the end section 12 of the top transverse sectional bar. The leg 11 has one end formed as a rivet 55

which extends through the top bar section 12 and it will be noted that the leg 11 extends entirely from the under side of the section 12 so as to leave the upper surface of the section 12 free of any projection which might otherwise interfere with the draping or suspension of the curtain thereover.

The end sections 12 have their end portions projecting forwardly, so as to improve the effect 10 produced by the suspended curtain. These two end sections 12 are formed as duplicates and thus their manufacture is facilitated. The legs 11 are then applied to the sections 12 so as to produce the right and left hand end sections.

15 It will be observed that the end sections 12 project beyond the uprights and that therefore the end sections may be recognized and described as of substantially T-form.

In the present case I have provided two middle sections 13 of the top transverse bar, these middle sections being curved with any desired contour so as to heighten the effect of the suspended curtain. The end and middle sections are all of hollow form. One of the sections 13 has 25 a reduced end portion 13a which is adapted to be inserted into the plain open end of the other middle section 13. The outer plain open ends of the middle sections 13 are adapted to receive the reduced end portions 12a of the end sections 30 12. The sections of the top bar are secured together by cotter-pins 14 which are attached to the sections by chains and which are adapted to extend through registering apertures 12b and 13b, after the sections are brought together. 35 These pins 14 and the chains to which they are attached do not produce any obstruction to the suspension of the curtain over the top bar.

More than one set of apertures may be provided between the end and middle sections 12 40 and 13 so as to permit the middle sections 13 to be turned about the horizontal axis and thereby change the plane of the curvature of the middle sections; that is to say, by proper adjustment the middle part of the top bar may be caused to 45 curve upwardly or rearwardly as may be desired. At the same time and as part of the same adjustment, the end sections will be turned about the vertical axis of their supports so as to vary the extent to which the outer end portions of the 50 end sections project forwardly. This adjustment is permitted by the manner of engagement of the legs 11 in their supports and is in co-ordination with the adjustment of the middle sections.

The curtain may be suspended by means of 55 hooks which are fastened to the curtain and which may be readily engaged over the top bar. Or, any other suitable means may be employed for suspending the curtain therefrom.

The number of middle sections of the top bar 60 may be varied according to the width of background desired. Thus, there may be employed a single middle section instead of the two middle sections herein shown or there may be employed more than two middle sections.

65 The variation of the width of the background, as above referred to, is permitted by the fact that the upright supports are independent of each other and can be placed at any distance apart according to the length of top bar employed.

70 Thus, I have devised a readily collapsible and adjustable curtain support that can be manufactured at a comparatively low cost and that can be employed in an extremely convenient and

efficient manner, with an adjustment that permits the configuration of the background to be varied in an extremely simple manner.

What I claim is:

1. A curtain support comprising a plurality of 5 collapsible uprights, said uprights being of duplicate construction independently separate from each other and each comprising telescoping sections, and a collapsible, sectional transverse top bar for suspension of the curtain, the top bar 10 comprising duplicate end sections and duplicate, curved middle sections, means depending from said end sections for supporting engagement within the upper end of the uprights, and means for detachably and adjustably connecting said 15 end and middle sections together.

2. A curtain support comprising a plurality of collapsible uprights, said uprights being of duplicate construction independently separate from each other and each comprising telescoping sections, and a collapsible, sectional transverse top bar for suspension of the curtain, the top bar 20 comprising duplicate bent end sections and duplicate curved middle sections, said middle sections being adjustable with respect to the end 25 sections about a horizontal axis so as to change the position of the plane of the curvature thereof, legs depending from said end sections for rotatable adjustable supporting engagement within the upper end of the uprights, said end 30 sections being rotatably adjustable in coordination with the adjustment of the middle sections, and means for detachably and adjustably connecting said end and middle sections together in 35 their different adjustments.

3. A curtain support comprising a plurality of collapsible uprights, said uprights being of duplicate construction independently separate from each other and each comprising telescoping sections, and a collapsible, sectional transverse top 40 bar for suspension of the curtain, the top bar comprising duplicate bent end sections and similarly curved middle sections, said middle sections being adjustable about a horizontal axis so as to change the position of the plane of the curvature 45 thereof, legs depending in T-like manner from said end sections for rotatable adjustable supporting engagement within the upper end of the uprights, said end sections being rotatably adjustable in coordination with the adjustment of 50 the middle sections, and means for detachably connecting said end and middle sections together in 55 their different adjustments, the entire top of the device being substantially free of projections upon its upper surface so as to afford a substantially continuously smooth surface for suspending the curtain therefrom.

4. A curtain support comprising a plurality of collapsible uprights, said uprights being of duplicate construction and being independently separate and adapted to rest directly upon the floor, and a collapsible sectional transverse top bar for suspension of the curtain, the top bar comprising 60 duplicate end sections and a curved middle portion adjustable with respect to the end sections about a horizontal axis so as to change the position of the curved middle portion, means depending from said end portions for supporting engagement within the upper end of the uprights, and means for detachably and adjustably connecting said end and middle portions together.

ROBERT R. DE MENT.
